GAS TURBINE PLANT

Wilbur H. Armacost, Scarsdale, and David M. Schoenfeld, New York, N. Y., assignors to Combustion Engineering Company, Inc., New York, N. Y.

Application February 10, 1945, Serial No. 577,245

3 Claims. (Cl. 60—59)

1

This invention relates to gas turbines and particularly to those in which the working fluid passes in heat exchange relationship with the gases and heating surface of a steam generating unit.

When employed with a steam generating unit the compressed working fluid for the gas turbine is heated indirectly by the products of combustion leaving the furnace of the steam generator. The products of combustion thereafter flow over various heating surfaces of the generator to be further cooled. Thus, the working fluid remains uncontaminated by impurities, such as ash, which would be present if it were made up, at least in part, of the products of combustion of a fuel. After leaving the heat exchanger, the working fluid is expanded through the turbine wherein it produces useful work and thereafter may be conducted back to the steam generating unit to there join with the products of combustion flowing through the generator.

An object of this invention is to provide an improved gas turbine including a steam generator.

In the drawing:

Figure 1 is a diagrammatic view of one form of the invention.

Figure 2 is a similar diagrammatic view of another form of the invention.

The drawing illustrates a steam generating unit comprising upper and lower drums 10, 11 connected by a bank of steam generating tubes 12 and an economizer 13 having tubes connected between inlet and outlet manifolds 14 and 15 all heated by a furnace 16 which is provided with a gaseous fuel burner 17. Feed water is supplied through pipe 9 to manifold 14 and manifold 15 connects to the steam and water drum 10.

In Figure 1 a single heat exchanger 20 is shown having tubular elements suspended in the furnace and connected between inlet manifold 21 and outlet manifold 22. In Fig. 2 there are two similar heat exchangers 20 and 23, the first corresponding to that of Fig. 1 and the second having tubular elements suspended also within the furnace and connected between inlet and outlet manifolds 24 and 25.

In Figure 1 an air compressor 30, a gas turbine 32 and an electric generator 34 all have their respective shafts fastened together by couplings 34A so that the turbine serves as a common drive for all. Air enters compressor 30 through conduit 31 and leaves the compressor to flow through conduit 33 to a heat exchanger 35. From heat exchanger 35, the air flows through conduit 37 to inlet manifold 21 of heat exchanger 20 and from

2

outlet manifold 22 through conduit 39 to gas turbine 32. From turbine 32 the air flows through the heat exchanger 35 and through conduit 38 to burner 17. A branch 36 from conduit 38 delivers a portion of the air into the boiler setting to join the products of combustion flowing therethrough.

In Fig. 2 an air compressor having a first stage 30 and a second stage 30A, a gas turbine having a first stage 32 and a second stage 32A and an electric generator 34 all have their respective shafts coupled. Air enters compressor stage 30 through conduit 31, is compressed, passes through intercooler 40 to second stage 30A and thence through conduit 33 to a heat exchanger 35. From heat exchanger 35 the air flows through conduit 37 into inlet manifold 21 of heat exchanger 20, and from outlet manifold 22 through conduit 39 to stage 32 of the gas turbine. From stage 32 the air flows through conduit 41 into inlet manifold 24 of heat exchanger elements 23 and from its outlet manifold 25 through conduit 43 to stage 32A of the gas turbine. From stage 32A the air flows through the heat exchanger 35 through conduit 38 and another heat exchanger 45 to burner 17. A branch 36 from conduit 38 delivers a portion of the air into the boiler setting to join the products of combustion flowing therethrough.

The feed water to the boiler enters through pipe 47 and divides, one portion flows through intercooler 40 to economizer inlet manifold 14, and thence into the steam and water drum 10. The other portion flows through pipe 48 into heat exchanger 45. Upon leaving heat exchanger 45 the water divides, one portion flowing through pipe 50 as hot water, for use other than in the boiler unit, and the other portion flows through pipe 51 to join the water leaving the economizer outlet manifold 15 flowing through the pipe to the steam and water drum 10.

In operation free air from compressors 30, 30A is delivered to heat exchanger 35 wherein it receives heat given up by the exhaust air from turbine stage 32, 32A, then flows through heat exchanger 20 and is delivered to turbine stage 32. In expanding through the turbine 32, 32A it loses heat which is converted into work used for driving the compressor 30, 30A and electric generator 34. After leaving turbine stage 32, 32A the air is cooled within heat exchanger 35 to a temperature suitable for use in the fuel burning apparatus to which that portion necessary for combustion within the furnace is conducted. The remaining surplus portion of this air is delivered into the setting of the boiler unit, to join the products

of combustion flowing through the unit, at a location where the products have been cooled to a temperature substantially that of the air.

According to the invention, heat exchanger 35 reclaims heat for use in the turbine from the exhaust of the air leaving the turbine in order to cool this air to a temperature suitable for use in the fuel burning apparatus. Heretofore this air was cooled by a heat exchanger through which cooling water was passed, and the discharged hot water was in part or wholly wasted, resulting in loss of heat from the combined turbo-boiler unit.

According to the invention there is a further thermal saving incurred by delivering the surplus portion of the air leaving heat exchanger 35 into the boiler setting through conduit 36 at a location where the products of combustion have been cooled to substantially the air temperature. Heretofore the surplus air was delivered into the furnace and therein mixed with the products of combustion. This procedure resulted in lowering the temperature of the products leaving the furnace, and a lower temperature difference between the products and heat absorbing tubes of boiler and economizer. Although the flow of products through the tubes was increased, the net result was a loss in the heat transferred to boiler and economizer. However, by introducing the surplus air according to the invention the products of combustion are undiluted up to the point within the boiler setting where the surplus air is introduced and a net gain in overall heat absorption by the unit from the products and the surplus air results.

Another advantage in using heat exchanger 35 in the manner described is that it may be made of relatively inexpensive materials, since it is exposed to low temperatures, when compared to the costly materials used in heat exchanger 28, 23 which is subjected to high temperatures. Since heater 35 assumes some of the air heating otherwise done by heater 28, the latter may be smaller thereby incurring a further saving in cost and proportionately also overcomes the objection of the removal of the dirt and slag deposits on the larger heater within the furnace which cause a variation in the heated air temperatures.

Further, in the form shown in Fig. 2, that portion of the air leaving heat exchanger 35 which is conducted to the burner 17 is further cooled by water flowing in indirect relation to the air in heater 45. The cooling water is taken from the boiler feed water supply pipe 47, conducted through heater 45 and thence conducted by pipe 51 to join the water leaving economizer outlet manifold 15 to flow into steam and water drum 18. Should the water required by the economizer 13, intercooler 40 and heater 45 exceed the demand of the boiler 18, the surplus may flow through pipe 50 for outside use. However, by this arrangement of using the relatively cold water for supplying heater 45, the temperature of the surplus water is kept to a minimum incurring a minimum heat loss from the unit.

What we claim is:

1. In a power plant having a gas turbine, a fluid compressor and a steam generator unit including an associated furnace, fuel burner and a setting for confining the flow of the products of combustion therethrough; first and second fluid heaters for heating the compressed fluid; con-

duits for conveying compressed fluid from the compressor to the first heater, from the first to the second heater, from the second heater to the turbine, from the turbine exhaust to first heater in out of contact relation to the compressed fluid flowing therethrough thereby cooling said exhausted fluid, and from the second heater to the burner, said last conduit having a branch delivering a portion of the fluid into the setting at a location where the products of combustion have been cooled to substantially the same temperature of the delivered fluid.

2. In a power plant having a gas turbine, a fluid compressor and a steam generator unit including an associated furnace, fuel burner and a setting for confining the flow of the products of combustion therethrough; first and second fluid heaters for heating the compressed fluid; and a third heat exchanger for cooling the fluid; conduits for conveying compressed fluid from the compressor to the first heater, from the first to the second heater, from the second heater to the turbine, from the turbine exhaust to first heater in out of contact relation to the compressed fluid flowing therethrough thereby cooling said exhausted fluid, and from the second heater to the third heat exchanger and thence to the burner, said last conduit having a branch in advance of the third heater, with respect to the fluid flow, delivering a portion of the fluid into the setting at a location where the products of combustion have been cooled to substantially the same temperature of the delivered fluid; a feed water pipe and a branch pipe from the feed water pipe to the steam generator to the third heat exchanger for cooling the fluid flowing therethrough in out of contact relation; a pipe from the third heat exchanger to the steam generator, and a surplus water pipe connected into the pipe from the third heat exchanger.

3. In a power plant having a gas turbine, a fluid compressor and a steam generator unit including an associated furnace, fuel burner and a setting for confining the flow of the products of combustion therethrough; first and second fluid heaters for heating the compressed fluid; and a third heat exchanger for cooling the fluid, conduits for conveying compressed fluid from the compressor to the first heater, from the first to the second heater, from the second heater to the turbine, from the turbine exhaust to first heater in out of contact relation to the compressed fluid flowing therethrough thereby cooling said exhausted fluid, and from the second heater to the third heat exchanger and thence to the burner, said last conduit having a branch in advance of the third heater, with respect to the fluid flow, delivering a portion of the fluid into the setting at a location where the products of combustion have been cooled to substantially the same temperature of the delivered fluid; a feed water pipe and a branch pipe from the feed water pipe to the steam generator to the third heat exchanger for cooling the fluid flowing therethrough in out of contact relation; an economizer; the feed water pipe being connected to the economizer and hot water pipe from the economizer to the steam generator; a pipe from the third heat exchanger to the hot water pipe leaving the economizer, and a surplus water pipe connected into the pipe from the third heat exchanger.
